N. C.

Continuation of application Serial No. 638,607,
October 19, 1932. This application February
14, 1935, Serial No. 6,597

8 Claims. (Cl. 217—122)

This application is a continuation of my application Serial No. 638,607, filed October 19, 1932, for "Baskets".

This invention relates to baskets particularly 5 adapted for the packing of fruit; and more particularly, to means for securing the cover to the basket.

It is customary to make the tops of baskets of this type of thin strips of flexible material laid 10 across each other to form a lattice effect, with a hoop extending around the under side and a slat passing across and beyond the extremity of the top adapted to fit under wire handles extending up from the basket. This leaves the opposite 15 sides of the basket unsecured and permits considerable play so that the hoop extending around the top may press into the apples and injure them. Apples are sold in this country largely by the color exposed in the top layer and the evenness of the 20 pack, so that to have the surface injured detracts from the value of the apples. Further, where the ring packed method is employed, it is usual to pack the apples with a contour, so that the center of the fruit will be the highest point. This 25 necessitates the use of a convex top.

Custom demands that apples shipped to Europe have a flat instead of an oval pack, and therefore, a flat top is used instead of the convex top. In connection with the side fastening means, it is 30 old to have a flexible metallic member fastened to the body of the basket and extending beyond the open end thereof, and a second flexible member secured to the upper surface of the cover and anchored at a substantial distance from the edge 35 with a loop, the bight of which extends beyond the edge of the cover in position to receive the flexible member secured to the body member.

This latter structure is illustrated by the patent to Leigh, No. 1,596,054. This structure, however, 40 is open to certain objections: First, the bight that extends beyond the edge of the basket is unsupported and does not present a rigid support; second, it is subject to being bent; third, since they extend on both sides beyond the edge of the 45 top they occupy valuable space, particularly where the baskets are shipped by the carload; fourth, being unsupported, the bights have a tendency to break off; and fifth, since the slat extending across the basket top must be inserted under the loops before the sides are fastened down, the flexible 50 member secured to the body of the basket often misses the loop secured to the top and the edges of the top must be bent up until the body resilient member can be inserted in the bight. This is particularly difficult where the loop on the basket top

extends out over the edge of the basket, since the distance to be cleared is that much greater.

One of the prime objects of my invention is to provide a basket which may be utilized for either an oval or flat pack, and at the same time, the 5 top will be held securely in position against side slippage.

Another object of the invention is to provide a fruit basket with projections spaced apart along the top edge thereof to support any cover therefore at a sufficient distance above said top edge to prevent crushing contact with the contents of the basket. 10

Another object is to provide securing means that will overcome the objections above enumerated. 15

Other objects will be disclosed in the specification and drawing forming a part of this application.

In the drawing:

Figure 1 is a fragmentary perspective of the basket with top in place; 20

Figure 2 is a vertical section taken on line 2—2 of Figure 1;

Figure 3 is a top plan of a modified form of 25 basket top and

Figure 4 is a detailed showing of the top fastening member removed from the top.

Referring to the drawing, in which similar parts are designated with like numerals:

Numerals 5 designate a basket of the type usually used in packing fruit having sides 6 composed of staves 7 and being held in place by a hoop 8. Projections 9 extend above the hoop 8 so that the cover 11 is at all times held away from crushing contact with the fruit or contents of the basket regardless of the pack. The space 12 between the projections 9 gives added ventilation to the surface of the apples. Wire loops 13 extend up from the hoop 8 to receive a slat 14 40 to hold the cover 11 in position. 30

Oppositely disposed to the loops 13 are flexible members 15 secured to the inside of the basket 5, the ends 16 extending through the basket 5 and hoop 8 being clinched on the outside of the hoop 45 8. U-shaped indents or notches 17 are formed in the cover 11 of the basket 5 and oppositely disposed to the flexible members 15. Anchored at a distance from the edge of the top 11 are U-shaped securing members 18, the bight 19 of said 50 members lying across said U-shaped indents 17, but spaced inwardly from the periphery of the cover 11. The legs 20 of the U-shaped members 18 are spaced from each other a sufficient distance to straddle the U-shaped indents 17. This 55

affords a support for the U-shaped securing members 18, except at the point where the bight extends across the indents 17, and thus affords a very strong and substantial construction.

- 5 Further, there is no projecting bight to be knocked off or catch in obstructions and to occupy valuable space. In case either of the members 15 should extend outside of the securing members 18 after the cover 11 has been secured 10 in place by way of slot 14, the edge of the cover 11 opposite the securing means may be raised and the flexible member 15 inserted through the securing member 18.

As actually used, the basket 5 will be packed 15 by one of the approved methods. In the case of the flat pack, they will extend up to top edge of the hoop 8, that being the top of the basket. In the case of an oval pack, the center will extend above the said edge. In either case, a flat 20 top may be utilized without injuring the pack and if a hoop is secured beneath the top, it is likewise spaced from the fruit.

The slat 14 will be slipped under the loops 13, the flexible members 15 taking the position shown 25 in dotted lines in Figure 2. The flexible members 15 will then be bent over the bight 19 of each member 18 and the top will be securely held in place against side slippage.

Figure 3 is a modified form of cover in which 30 a hole 17' is formed instead of the indents. The cover 11 overlaps the basket 5 so that the hole 17' will be in line with the flexible members 15. Upon the flexible members 15 being inserted in the opening 17', the flexible members will be bent 35 over to secure the cover in position.

What I claim is:

1. A shipping container for fruit or the like, comprising a basket body having a hoop defining an open top, and projections spaced apart along 40 and extending above said top to support a cover out of contact with the contents of said body.

2. A shipping container for fruit or the like, comprising a basket body having a hoop defining an open top, opposite sides of said body having 45 projections extending above said top to support a cover out of crushing contact with the contents of said body.

3. A fruit basket comprising a body having spaced apart projections extending above its top edge, a cover supported by said projections, and 50 means for detachably securing the cover to said body.

4. A shipping container comprising a body

having a hoop defining its top edge and a cover therefor having notches formed in the periphery thereof, securing members anchored in said cover and having bights spaced inwardly from the periphery of said cover and lying across said notches 5 and flexible members anchored in said hoop and extending upwardly through said notches inside of said bights and adapted to be bent over said bights to secure said cover in closing position on said body.

5. A shipping container comprising a body, a hoop defining its top edge, and a cover therefor having notches formed in the periphery thereof, projections spaced apart on the top edge of said body to support the cover out of contact with the 15 contents of a filled body, securing members anchored in said cover, and having bights spaced inwardly from the periphery of said cover and lying across said notches, and flexible members anchored in said hoop, and extending upwardly 20 through said notches inside of said bights and adapted to be bent over said bights to secure said cover in closing position on said body.

6. A fruit basket having its sides formed by staves, a hoop extending around said staves, the 25 upper ends of some of said staves being substantially flush with said upper edge of said hoop and forming therewith the top edge of said basket, others of said staves extending above said upper edge to form projections spaced apart along said 30 top edge to support a cover out of contact with the contents of the basket.

7. A fruit basket having its sides formed by staves, a hoop extending around said staves, the upper ends of some of said staves being substantially flush with said upper edge of said hoop and forming therewith the top edge of said basket, others of said staves extending above said upper 35 edge to form projections spaced apart along said top edge, and a cover supported by said projections. 40

8. A fruit basket having its sides formed by staves, a hoop extending around said staves, the upper ends of some of said staves being substantially flush with said upper edge of said hoop 45 and forming therewith the top edge of said basket, others of said staves extending above said upper edge to form projections spaced apart along said top edge, a cover supported by said projections, and means for detachably securing the 50 cover to the body.
